ATTORNEYS.

UNITED STATES PATENT OFFICE.

HERBERT H. DOW, OF MIDLAND, MICHIGAN, ASSIGNOR TO THE DOW CHEMICAL COMPANY, OF MIDLAND, MICHIGAN, A CORPORATION OF MICHIGAN.

COKING PROCESS.

Application filed September 12, 1918. Serial No. 253,710.

To all whom it may concern:

Be it known that I, HERBERT H. Dow, a citizen of the United States, and a resident of Midland, county of Midland, and State of Michigan, have invented a new and useful Improvement in Coking Processes, of which the following is a specification, the principle of the invention being herein explained and the best mode in which I have contemplated 10 applying that principle, so as to distinguish it from other inventions.

The present improvements have more particular regard to a method of treating coal in a generator, in which the material is being 15 constantly agitated or turned over. A further stage of the process gives producer gas, by continuing such operation, while air and steam are supplied to the material being treated. The invention also involves a suitable 20 apparatus for carrying on such process. Thus it consists of the steps and means hereinafter fully described and particularly pointed out in the claims, the annexed drawing and the following description setting 25 forth in detail certain steps and mechanism embodying the invention, such disclosed steps and means constituting, however, but one of the various ways in which the principle of the invention may be used.

80 In said annexed drawing:—

Fig. 1 is a central vertical section through a generator embodying my present improvements and adapted to carry out my improved process; Fig. 2 is a transverse section 35 of a detail taken on the plane indicated by the line 2—2, Fig. 1; and Fig. 3 is a similar section taken on the plane indicated by the line 3—3, Fig. 1.

As shown in the aforesaid drawing, my 40 improved generator consists in effect of a large tumbling barrel 1 which is preferably, for the sake of strength and other reasons, given the spherical form shown in Fig. 1. Such barrel is mounted to rotate about an inclined axis $a-a$, preferably an axis inclined 45 at an angle of about forty-five degrees. To this end the shell is provided with a solid trunnion 3 extending downwardly, and a hollow trunnion 2 upwardly which are journaled in suitable bearings (not shown) disposed on an axis as stated. Such upper trunnion will also be provided with connections such as shown for instance in my Patent No. 957,314 or No. 961,216, whereby gases may be 50 withdrawn from the interior of the genera-

tor. The latter is lined with acid refractory material, for example silica, preferably in the form of brick 4, and is provided with a suitable manhole 5 having a detachable cover 6 through which the material to be treated 60 may be supplied to its interior. To relieve the trunnions of a portion of the load, a roller 7 or plurality of rollers co-operating with a band or rail 8 on the exterior of the shell may be utilized, as may be readily understood.

In addition to the provision made as just described for withdrawing gases from the interior of the generator, through the hollow trunnion 2, means are also provided for optionally introducing steam or air into the mass of material in the generator, such means consisting of a plurality of holes 9 through the shell and lining of the retort adjacent the other trunnion 3. A commutating ring 75 10 surrounding such trunnion normally seals these openings, with the exception of the lowermost three (or smaller or larger number if desired), with which a passage 11 in such ring communicates. This passage is in 80 turn connected with a supply either of air or steam, as will be readily understood, whereby the one or the other may be injected into the bottom of the mass of material in the generator.

Assuming the generator to be used as a retort, proper, the operation can be readily indicated. The interior will be maintained at all times approximately half full of coke in more or less ignited or else incandescent condition. Upon the addition of fresh coal and the slow rotation of the generator, all the volatile products of such coal will be driven off, as in a regular coking process. When the temperature then subsides a little, air or 90 steam is admitted, with the result that producer gas is formed, which is switched into a suitable container for use as desired. After this operation has progressed far enough, a portion of the coke is dumped, more coal 100 added, and the sequence of steps repeated as before.

My improved generator, it will hence be seen, may be operated as a by-product coking proposition, practically the full proportion of benzol and other volatile hydrocarbons being recovered. Following the elimination of these valuable constituents the retort is then continued in operation as a gas producer apparatus, the surplus coke which 110

is withdrawn from time to time being of an excellent quality, although somewhat ground up as a result of the rotation of the generator.

5. The process or method involved in the operation of my improved generator may be more specifically restated as follows; viz. Assuming, at the start, that the generator is partially filled with coke at a relatively high 10 temperature i. e., one at which said coke is incandescent and the walls of the generator also heated to a high corresponding temperature, the generator is so rotated that the opening is on the upper part and a 15 charge of coal is introduced, the amount introduced being materially less than the amount of incandescent coke already in the generator. Gas is immediately given off in a manner similar to that where coal is 20 shoveled into a stationary gas retort. The door is then closed and the generator is slowly rotated whereby a more or less intimate mixture of the incandescent coke and coal is produced and the various parts of 25 the hot wall of the generator are successively brought in contact with the coal and coke mixture. When the evolution of gas is no longer sufficient to warrant further agitation, steam (or steam and air mixed) is 30 blown into the generator and an ordinary water gas or producer gas is formed. The temperature of the interior is then at a minimum and a certain percentage of the charge is removed and either utilized in an ordinary 35 gas producer or in such other way as may be desired. The relatively cold charge is then brought up to the maximum temperature by blowing air. The cycle is then repeated.
40. Through such operation may result the production of three types of coal gas. The first of the latter is the kind of gas that is given off when the generator contains a fresh charge of coal, the generator being

heated if necessary, and it consists of the 45 volatile constituents of the coal and is made up of a considerable proportion of aromatic hydrocarbons. The second gas produced is water gas similar to that produced in artificial gas plants when incandescent coke or 50 anthracite coal is blown with steam; while the third gas thus produced is similar to ordinary producer gas where steam is not used. This last gas is of low calorific value and is relatively high in nitrogen. 55

Other modes of applying the principle of my invention may be employed instead of the one explained, change being made as regards the steps herein disclosed, provided those stated by any one of the following 60 claims or their equivalents be employed.

I therefore particularly point out and distinctly claim as my invention:—

1. In a method of treating coal and like material in a generator, the steps which consist in first heating the same to drive off the larger portion of the more readily volatilized constituents contained therein, blowing steam through such material to form water gas and incidentally cool the material, removing a portion of the partially cooled coke, admitting air to form producer gas and raise the temperature of the material, and then adding a fresh charge of material. 65

2. In a method of treating coal and like material in a generator, the steps which consist in mechanically mixing a fresh charge of such material with a charge previously heated to a high temperature, thereby driving off the larger portion of the volatile 70 constituents of such fresh charge, and then passing steam and air successively through the resultant mixture to form water gas and producer gas therefrom, respectively. 75

Signed by me, this 24th day of August, 80
1918.

HERBERT H. DOW.
